CLAIM

The ornamental design for a root canal meter, as shown and described.

DESCRIPTION

1. Root canal meter

1.1 : Front

1.2 : Back

1.3 : Top

1.4 : Bottom

1.5 : Right

1.6 : Left

1.7 : Front perspective view 1

1.8 : Front perspective view 2

1.9 : Back perspective view 1

1.10 : Back perspective view 2

1.11 : Perspective view shown in an environment of use

1.12 : Perspective view shown in another environment of use

The article is equipment for measuring and displaying a root canal length of a tooth during root canal treatment which is a type of dental treatment methods; reproduction 1.12 shows the state in which the high-frequency treatment module is attached to the article, and the high-frequency treatment module is shown by means of broken lines and forms no part of the claimed design; the parts shown by means of broken lines in the reproductions are not part of the claimed design; the parts having oblique parallel lines in the reproductions 1.11 are transparent; the oblique parallel lines depict environment and form no part of the claim.

1 Claim, 12 Drawing Sheets
